UNITED STATES PATENT OFFICE.

JOHN J. DONNELLY, OF DENVER, COLORADO.

AERIAL APPARATUS OF THE HEAVIER-THAN-AIR CLASS.

989,496.

Specification of Letters Patent. Patented Apr. 11, 1911.

Application filed August 9, 1909. Serial No. 511,855.

To all whom it may concern:

Be it known that I, JOHN J. DONNELLY, a citizen of the United States, residing in the city and county of Denver and State of Colorado, have invented certain new and useful Improvements in Aerial Apparatus of the Heavier-Than-Air Class; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in aerial apparatus of the heavier than air class, and includes a suitable motor connected in operative relation with a pair of shafts, one passing axially through the center of the other, the shafts being extended upwardly, and each being equipped with a propelling wheel, composed of a series of blades, as hereinafter set forth, more in detail. The two propellers coöperate to draw the machine in the same direction, and they are rotated in opposite directions, their blades or fans being inclined accordingly. In my improved construction, the lower propeller is smaller than the upper, and rotates more rapidly. The blades of the upper propeller are discontinued, as their ribs or arms approach the center of rotation, thus allowing the air to pass downwardly freely. As the inner extremities of these blades have little motion, as compared with their outer extremities, it is believed advantageous to construct the upper propeller blades in the manner aforesaid, thus doing away with what would otherwise be practically inactive portions of the blades, owing to the slow movement of these portions, as compared with the movement of the outer portions of the blades. Another advantage is that the lower wheel running at a higher speed than the upper one, works with greater efficiency in the downward current already formed by the upper propeller. Furthermore, in my present invention, the ends of the blades are farther from the shaft or axis of rotation, are lowered, giving each propeller a parachute shape. The purpose of this is to obtain a certain amount of pressure of air beneath the propellers and permit the lower propeller to operate in air while compressed. The center of the smaller propeller is cov-

ered so that the compressed air cannot escape upwardly through that part of the propeller which would necessarily be inoperative, owing to its comparatively slow movement. This feature also gives an important parachute effect in descending whether by accident or design. This covering should be of silk or some similar light material. The extent of the area covered should be determined by the requirements of efficiency. In my improved construction, the blades bow along the line of the radius, compressing the air to the center of the blade and preventing its escape either beyond the area of the propellers or through the slowly moving center. Looking at the blade from beneath, it appears concave to a line running from the shaft to the circumference. In the construction of the blades, they should as far as convenient be bent transversely upwardly in the line of their movement when operating, so that looking from beneath, they would be convex to the line of their movement. The purpose of this construction is to decrease the resistance of the air in the line of the plane of the propeller in proportion to the resistance obtained in the line of the shafts. This is the opposite of the purpose of the construction of the blades of a windmill, which is to develop resistance of air in the line of the plane of movement of the device.

Still another novel feature of my present construction consists in the fact that the upper and larger propeller is attached to and driven by the outside shaft, the upper extremities of the ribs of the blades, however, being journaled on the inside shaft, which extends for this purpose above the lower propeller, the object being to permit both propellers to be brought comparatively close together, and still braced from below, securing a light and strong construction.

Having briefly outlined my improved construction, I will proceed to describe the same in detail, reference being made to the accompanying drawing, in which is illustrated an embodiment thereof.

In this drawing: Figure 1 is a side elevation of an aerial apparatus, illustrating my improved construction. In this view, no attempt has been made to show a car for the purpose of carrying passengers, only such features being brought out as are necessary in the illustration of the novel features covered by the present application. Fig. 2 is a

top plan view of the same, a number of the blades of the upper propeller being broken away to permit of better illustration of the lower propeller.

5 The same reference characters indicate the same parts in all the views.

Let the numeral 5 designate a suitable framework in which is journaled a center shaft 6, and a hollow shaft 7, through which 10 the shaft 6, passes. These two shafts are equipped with gears 8 and 9 respectively, which mesh with gears 10 and 12 respectively, fast on shafts 13 and 14. The shaft 15 13, is continuous with the operating shaft of an engine 15. Upon this shaft is mounted and made fast a gear 16, which meshes with a smaller gear 17, fast on the shaft 14. By virtue of this gearing, the two shafts 6 and 7 are rotated in opposite directions. To the 20 upper extremity of the shaft 7, are secured the lower extremities of tie rods or wires 18, whose upper extremities are connected, as shown at 19, with the lower ends of blades 20 of the upper propeller. Connected with 25 these blades are bows or ribs 21, whose upper extremities are connected with a ring or collar 22, journaled on the upper end of the shaft 6. The lower propeller is made fast to the shaft 6, about midway of its length, by 30 means of tie rods or wires 23, whose lower extremities are connected with a collar 24, made fast on the last named shaft. The upper extremities of the rods 23, are connected, as shown at 25, with the lower ends of the 35 blades 26 of the lower propeller. The upper extremities of these blades are suitably connected with a collar 27, fast on the shaft 6. The inner extremities of the blades of the upper propeller are vertically discontinued, 40 the said blades being connected with the collar 22, only by the ribs 21. The reason for this construction is that if the blades were continued to the collar 22, their inner extremities would be practically useless, by 45 reason of their slow movement, as compared with the movement of the outer portions of the blades. It is thus found that the inner extremities of these blades if continued would be a hindrance, or reduce the efficiency 50 of the apparatus for the purpose intended.

The inner extremities of the blades 26, of the lower propeller extend inwardly into the open area below the rib extension 21, of the upper propeller, and may be given sufficient 55 speed to coöperate with the upper propeller blades to such an extent as to produce a machine of far greater efficiency than where a single propeller alone is employed, or where 60 two propellers are employed, both having blades extending inwardly to the shaft. Furthermore by doing away with the inner extremities of the propeller blades, the apparatus is made much lighter than where 65 these blades extend to the shaft, as will be readily understood. Therefore, in my im-

proved construction, I lessen the weight of the apparatus without a loss of efficiency, which is considered an important feature in apparatus of this character.

From the foregoing description, the operation of my improved construction will be readily understood. Assuming that the engine is in operation, the rotation of its shaft through the medium of the gearing heretofore explained, will impart rotation to the 75 shafts 6 and 7, in reverse directions, it being my intention to rotate the lower propeller which is carried by the shaft 6, at a greater speed than the upper propeller, the differential being sufficient to cause the lower propeller to do the same work or approximately the same work as the upper propeller, while having blades of considerably less area and extending farther inwardly toward the center or axis of rotation. By virtue of the 80 peculiar shape of the blades 20 of the upper propeller, whereby they are bent or bowed longitudinally, the air is driven inwardly, toward the center of the apparatus and somewhat compressed, thus giving the blades 90 of the lower propeller a resistance medium of greater density than normal atmospheric air, thereby increasing the efficiency of the operation of the lower propeller. Furthermore, by virtue of the longitudinally bowed 95 or bent shape of the blades 20, of the upper propeller, a better parachute result is obtained during the descent of the apparatus.

Attention is called to the fact that the central portion of the lower propeller is covered 100 between the inner extremities of the blades 26 and the shaft, in order to facilitate the parachute effect during the descent of the apparatus. This covering is designated 28.

Having thus described my invention, what 105 I claim is:

1. An aerial apparatus, comprising two shafts coaxially journaled, and propellers consisting of a series of radial arc-shaped blades, one propeller being smaller than the other, the smaller propeller being fixedly connected with the shaft and mounted to rotate beneath the larger propeller, the larger propeller being journaled on the central shaft, and fixedly connected with the outer shaft and arranged to rotate in opposite directions to the smaller propeller, and a motor connected in operative relation with the said shafts, substantially as described.

2. Aerial apparatus, comprising a framework and motor, shafts coaxially journaled in the framework, the central shaft protruding beyond the outer shaft, a connection between the motor and the shafts to cause them to rotate in opposite directions, propellers mounted on the shafts and having radially arranged arc-shaped propeller blades, one of the propellers being smaller than the other and mounted to rotate beneath the larger propeller, the larger propeller being jour-

naled on the central shaft, and having connecting rods connecting the outer extremities of its blades with the outer shaft, while the smaller propeller is mounted on the protruding portion of the central shaft, the propeller blades of the larger propeller being discontinued at the center of rotation, while the blades of the smaller propeller extend entirely to their center of rotation, and a covering for the inner extremities of the propeller blades of the smaller propeller, for the purpose set forth.

3. Aerial apparatus comprising two shafts coaxially journaled, means for rotating the shafts in opposite directions, propellers mounted upon the shafts, one of the pro-

pellers being smaller than the other, the said propellers consisting of radially arranged arc-shaped blades, the smaller propeller being fixedly connected with the central shaft 20 below the larger propeller, the larger propeller being journaled on the central shaft, and connecting rods fixedly connecting the other extremities of the blades with the outer shaft, substantially as described.

In testimony whereof I affix my signature in presence of two witnesses.

JOHN J. DONNELLY.
